Chas. B. & W. Siger Design for Shoes.
Patented Aug. 4, 1847.

Des. 146

George W. Sizer & Henry Sizer Springfield Mass.
Letters Patent (Design No. 146) Dated 4th Sept. 1847

The schedule referred to in these Letters Patent and making part of the same.

To all whom it may concern: Be it known that we George W. Sizer and Henry Sizer of Springfield in the County of Hampden and State of Massachusetts, have invented or produced a new and ornamental parlor stove, and we do hereby declare the following to be a full and exact description of the same, reference being had to the accompanying drawings making a part of this specification.

The nature of our invention consists in the production of an ornamental stove, by the combination of the several designs and configurations on the various parts thereof, as herein set forth. The stove is of an oval form vertically.

Fig. 1. in the accompanying ^{drawings} is a perspective elevation of our ornamental stove. The top of the same is ornamented by the fancy moldings marked. Fig 2, 3 & 4 of which is an enlarged view as shown in the sectional drawings Fig 2, 3 & 4 and corresponding to the parts marked with the same figures upon the perspective view of the stove Fig. 1.

Dec. 1864

The section of the stove from 6 to 6 Fig. 1, is made usually of sheet iron, the other parts of cast iron. Fig. 5 is an ornamental ring resting upon the top of the ornamental base marked B. Fig. 6, is a moulding running around the top of what we term the bottom plate of the stove. The part marked A, represents the ornamental open work of the bottom, or hearth plate of the stove.

The part marked B, represents that part of the stove intended to contain the fuel, and is ornamented in gothic style and other fancy figures.

What we claim as original and desire to secure by Letters Patent is the general design and combination of the several figures of our stove as herein represented and set forth.
